UNITED STATES PATENT OFFICE.

SAMUEL KJELLGREN, OF ROCKFORD, ILLINOIS, ASSIGNOR OF ONE-HALF TO ROCKFORD CHAIR & FURNITURE COMPANY, OF ROCKFORD, ILLINOIS, A CORPORATION OF ILLINOIS.

EXTENSION-TABLE.

1,148,907.

Specification of Letters Patent. Patented Aug. 3, 1915.

Application filed June 3, 1914. Serial No. 842,748.

To all whom it may concern:

Be it known that I, SAMUEL KJELLGREN, a citizen of the United States, residing at Rockford, in the county of Winnebago and 5 State of Illinois, have invented certain new and useful Improvements in Extension-Tables, of which the following is a specification.

This invention relates in general to tables 10 and more particularly to extension tables wherein the table top is composed of relatively movable sections adapted to be moved to extended positions to provide a larger table top area.

15 One of the primary objects of my invention is to provide folding supporting legs for extensible table top-sections, and to provide novel means for automatically moving the legs to operative and inoperative positions upon movement of the table top-sections to extended and closed positions respectively.

Another object is to provide leg operating 25 means of simple construction so that these means will be inexpensive to manufacture, and to arrange the movable parts of the leg operating means so that they will form a durable and practical structure.

A further object of my invention is to 30 provide means for automatically locking the legs in their raised position, wherein the weight of the legs will effect the locking.

A further object is to provide an extensible top-section with supporting drop-leg 35 mechanism constructed so as to permit the top-section to be extended any desirable distance, and to serve as a support for the top-section during movement of the same while it is in an extended position.

40 A further object is to provide top-section supporting legs and means for operating them, of such construction that they may be readily and easily applied to tables having varying numbers of slide extensions.

45 Referring to the drawings: Figure 1 is a plan view taken on the line 1-1 of Fig. 2 of an extension table embodying my invention, one or the top-sections of the table being shown in an extended and the other in 50 a closed or inner position. Fig. 2 is a vertical sectional view taken on the line 2-2 of Fig. 1. Fig. 3 is a view similar to Fig. 2 but with the extended top-section moved to

a partially closed position. Figs. 4, 5, and 55 6 show the top-section in different successive stages of its movement to a closed position, the latter figure showing the section completely closed and the legs locked in folded position, and Fig. 7 is a vertical transverse sectional view taken on the line 60 7-7 of Fig. 2.

Extension tables which have their tops divided into sections movable relatively to vary the size of the table top, are provided with telescoping slides which slidably connect the 65 table top-sections and permit relative movement thereof, the number of slides differing in various tables depending upon the size and desired extensions of the table. While I have illustrated my invention on the 70 drawings as applied to an extension table having double slide extensions, it will be obvious that my improved supporting legs and the means for operating them are designed to be applicable to extension tables 75 embodying any number of slides without changing the table or slide construction.

The table illustrated is of the well known extension type comprising a base 8, a pedestal or support 9, a cross-board 11 carried by 80 the pedestal, slides carried by the cross-board, and table top-sections 12 and 13 carried by the slides. The slides include stationary members 14 fixed to the top-board 11, and members 15 and 16 slidably associated in a telescoping manner well known in the art, the members 16 being fixedly attached to the top-sections 12 and 13. With this construction each table top-section is 85 90 slidable from a closed to an extended position, and vice versa.

Each top-section is provided with a pair of legs for supporting the sections when they are in their extended positions, and with means for automatically moving the 95 legs to lowered and raised positions during movement of the top-sections to extended and closed positions respectively. Since the supporting legs and means for operating the same of each top-section are similar, I will 100 describe in detail the construction and operation of only those associated with the top-section 12, like reference numerals applying to like parts of each top supporting device.

105 A rock-shaft 17 is mounted transversely

of the slides in bearings 18 carried by the top-section 12, and has fixedly connected to the ends thereof legs 19 and 20, each of which is provided at its lower end with a 5 caster-wheel 21. The leg 20 has an arm 22 extending beyond its connection with shaft 17, adapted to be operated to rock said shaft and swing the legs to their several positions. The means for operating arm 22, which 10 means may be termed leg operating means, comprise a longitudinally slidable rod 23 mounted in guide-brackets 24 and 25 fixed to the top-section and the outer side of the slide member 16, said rod being pivotally connected to the arm 22 through the intermediary of a link 26 pivotally connected at its opposite ends 30 and 30' to ends of said arm and rod respectively. The rod 23 has a roller 27 at its link-connected end adapted 15 to roll upon the under face of the top 12 and guide the rod end as it is moved longitudinally to effect operation of the supporting legs. The longitudinal movement of the rod is positively controlled by coöperation 20 of the rod with cam-faces or guides during movement of the table top-section to its several positions, as will be hereinafter described.

When the table top-section 12 is in its extended position shown in Fig. 2, the leg 20 will be in an upright supporting position and the rod 23 will be held from longitudinal movement in one direction by its roller 27 abutting the guide-bracket 25 and from 25 longitudinal movement in the opposite direction by engagement of its downturned end 28 with the stop 29 which is fixedly attached to the slide member 15. It will thus be observed that the legs are securely locked 30 in their upright position. To further assist in locking the legs in this position the rod 23 is provided with a recess or notch 31 adapted to engage with the guide-bracket 24. It will be seen that when the top-section 12 is 35 moved inwardly, that is, in a closing direction, the rod 23 will be retained in its locked position by engagement with the guide-bracket 24, thus maintaining the legs in an upright and supporting position during 40 movement of the top-section inwardly. The top-section is supported in this manner until it has been moved inward a predetermined distance, whereupon the rod 23 will be operated automatically to swing the legs to a 45 raised position adjacent the underside of the table top. This operation of the rod is effected by the end 28 of the rod riding upon the inclined cam-face 32 carried by the cross-board 11, so as to elevate the inner end 50 of the rod to disengage its notch 31 from the guide-bracket 29, as shown in Fig. 3. When the rod end is moved inwardly until it abuts the raised end 33 of said cam-face, continued inward movement of the table 55

top-section will cause the rod to move longitudinally relatively to the top-section, thus swinging the legs upward in the manner shown in Fig. 4. Continuing the inward movement of the top-section the legs will be swung to a completely raised position 70 wherein the roller end 27 of the rod will have moved past vertical alinement with the pivotal connection 30 between the rod and leg 20. When the roller end has passed this alinement and is limited from further movement by the stop 35, the upward movement of the legs will be stopped, and weight of the suspended legs will effect locking of the legs in their raised position; in fact, a toggle-lock is effected as is shown by the relation of the several parts in Fig. 5. During the latter part of the longitudinal movement of the rod, its end 28 will be raised from engagement with the stop 33 by the rod having an inclined cam-face 34 which 75 rides upon the guide-bracket 24 by said movement of the rod, effecting raising of the rod end at approximately the same time the legs have reached their raised locked position, the relative position of the parts at 80 this stage of the top-section closing movement being clearly shown in Fig. 5. With the legs thus raised and locked, the top-section may be moved to its closed position 85 shown in Fig. 6.

When moving the table top-section to its extended position the legs will be carried raised until the down-turned rod end 28 strikes the stop 29 carried by slide member 15, thereby moving the rod longitudinally 90 in the direction opposite to the top-section movement and carrying roller-end 30' to the opposite side of vertical alinement with the pivot 30, whereupon the legs will drop to an upright position. A coiled spring 36 mounted upon shaft 17 and having its opposite ends attached respectively to the shaft and a bracket 18, serves to cushion the dropping of the legs so that the caster-wheels and leg mechanism will not be injured when the 95 caster-wheels strike the floor. The slide members 15 will be limited in their outward movement when they reach the position shown in Fig. 1, by suitable stop means (not shown) the use and construction of 100 which are well known in the art. The extended position of top-section 12 is determined by engagement of the rod end 28 with the fixed stop 29 as shown in Fig. 2, wherein the roller 27 abuts the bracket 25 105 and the rod-notch 31 engages with the bracket 24 thereby locking the top-section 110 from further extension and the legs in their upright position.

While I have illustrated my improvements attached to a table having double extensible slide members, it is my intention to use my improvements with tables having 115

either single slide extensions or a greater number than is shown in the drawings. In the former case, which would in fact be an elimination of the slide members 15, it will 5 be manifest that with the table top-section extended the rod end 28 would be located adjacent to the cam 32, so that raising of the legs would be commenced at a very short interval after initial movement of the top- 10 section inwardly. In using a plurality of any number of slide members to permit greater extension of the table top, the operation of the supporting legs would be as that described in detail above, it being obvious 15 that any number of intermediate slide members may be used, the stop 29 always being carried by the slide member associated with the table top-connected slide member.

I claim as my invention:

20 1. In an extension table, the combination of a central support, an extendible top-section mounted thereon, a supporting leg pivotally mounted on the top-section, and means for automatically moving the supporting leg to raised and lowered positions by moving the top-section with respect to the central support, said means including a rod mounted on the top-section to slide longitudinally thereon, a link pivotally connecting the outer end of the rod and the supporting leg and arranged to move past a dead center position with respect to the top-section when the rod has been moved with respect to the top-section to its most outward position so as to effect locking of the leg in raised position, abutment means mounted on the central support in the path of the inner end of the rod whereby when the top-section is moved inwardly said inner end of the rod will abut against the last named means and effect swinging of the leg to raised locked position, and means for disengaging said inner end of the rod from said abutment means to permit the top-section to 45 be further moved inwardly.

2. In an extension table, the combination of a central support, an extendible top-section mounted thereon, a supporting leg pivotally mounted on the top-section, a member carried by the top-section to move longitudinally thereon, a link pivotally connecting the outer end of said member and the supporting leg and arranged to be moved past a dead center position with respect to the vertical by movement of said member longitudinally to swing the leg to raised position, means for locking said member fixedly from longitudinal movement with respect to the top-section when the same is extended and the supporting leg is in lowered position, cam means carried by the support and with which the inner end of said member cooperates when the top section is moved inwardly, for releasing the member from

its said locked position, and means for moving the member longitudinally relative to the top-section to move the leg to its raised position and thereby move said link past said dead center position to effect locking of the leg in raised position. 65

3. In an extension table of the character described, an extendible table top-section, a supporting leg pivotally mounted on the top-section, a member mounted to move longitudinally on the top-section, a link pivotally connecting said member with the leg so that the latter will be swung on its pivot by longitudinal movement of said member with respect to the top-section, said link being arranged to move past a dead center 70 position with respect to the vertical when the leg has been moved to raised position by outward movement of said member, and means for stopping said member from moving outwardly when the link has been moved past said dead center whereby to effect locking of the leg in raised position. 75

4. An extension table of the character set forth, having means for automatically moving a table top-section supporting leg to lowered and raised positions by movement of the table top-section to extended and inner positions, respectively, comprising, in combination, a leg-connected member mounted to slide longitudinally on the top-section for swinging the leg to raised and lowered positions, means for locking said member fixed from longitudinal movement with respect to the top-section when the same is in its extended position and the leg 90 is in lowered top-supporting position, stationary cam means for operating directly upon the inner end of said member as the same is moved inwardly by movement of the top-section inwardly for releasing said 95 member from locked position, and means for sliding the member longitudinally on the top-section to raise the leg. 100

5. An extension table of the character set forth, having means for moving a table top-section supporting-leg to lowered and raised positions automatically by moving the top-section to extended and inner positions respectively, comprising, in combination, a member mounted to slide longitudinally on the top-section to operate the leg, means including a pivotal link connection between the outer end of said member and the leg arranged to maintain said member, with the top-section in its inner position and the leg raised, locked from leg-operating movement in one direction whereby the leg is maintained locked in its raised position but movable in the opposite direction to effect lowering of the leg, and means having no permanent operating connection with said member for moving said member longitudinally with respect to the top-section in 110 115 120 125

said opposite direction during movement of the top-section to its extended position whereby said member will release said link from locking position, thus permitting the leg to swing to lowered position.

6. In an extension table, the combination of a support, a table top-section slidably mounted thereon to move laterally toward and away from the support, a supporting leg pivotally mounted intermediate its ends on the top-section, a rod slidably mounted intermediate its ends on the top-section so as to move longitudinally thereon in the direction of the top-section movement, a roller 10 mounted on the outer end of the rod to roll upon the underside of the top-section, a link connecting said roller end of the rod with the upper end of the leg whereby the leg will be swung on its pivot when the rod is 15 in upright position, and stationary cam-means arranged in the path of the inner end of the rod and with which said end engages when the top-section is moved inwardly, for releasing the rod from its locking position 20 and for moving the rod longitudinally with respect to the top-section to swing the leg to raised position.

7. In an extension table, the combination of a central support, a top-section movable 30 laterally toward and away from the support, a supporting leg pivoted intermediate its ends on the top-section, a rod connected at one end to the upper end of the leg and carried longitudinally movable on the top-section, means holding the rod from longitudinal movement and thereby holding the leg locked in upright position whereby the top-section may be moved toward the support with its supporting leg locked from swinging 35 in either direction, stationary means located in the path of the inner end of the rod for moving the same out of its locking position when the top-section has been moved inwardly and for preventing longitudinal 40 movement of the rod with respect to the support whereby upon continued inward movement of the top-section its supporting leg will be swung to raised position.

8. In an extension table, the combination 50 of a central support, a top-section movable laterally toward and away from the support, a supporting leg pivotally mounted on the top-section, a longitudinally movable rod carried by the top-section, a link connecting 55 the outer end of the rod with the leg and being so arranged that when the rod has been moved longitudinally with respect to the top-section to its most outward position the link will be moved past a dead center position and effect locking of the leg in raised 60 position, whereby the top-section may be moved toward and away from the central support with the leg locked up, and means for preventing longitudinal movement of

the rod outwardly with respect to the central support after the top-section has been moved outwardly a predetermined distance so that upon continued movement of the top-section outwardly the said link will be retracted by reason of the relative movement 65 between the leg and rod, permitting the leg to swing to lowered top-supporting position.

9. In an extension table, the combination of a central support, an extension top-section, a supporting leg pivotally mounted on 70 the top-section, a longitudinally movable rod arranged beneath the top-section to move in the direction of the sliding movement thereof, the rod being connected at its outer end with the leg for swinging the same to raised 75 and lowered positions by longitudinal movement relative to the top-section, means carried by the top-section for locking the rod against longitudinal movement when the leg is lowered whereby to lock the leg in top-supporting position, cam-means mounted on the central support in the path of the inner end of the rod for releasing the same 80 from its locked position when the top-section has been moved inwardly a predetermined 85 distance, and means for preventing inward movement of the rod whereby upon continued inward movement of the top-section the leg will be swung to raised position.

10. In an extension table, the combination of a central support, an extension top-section, a supporting leg pivotally mounted on the top-section to move in the direction of the sliding movement thereof, the rod being connected at its outer end with the leg for 90 swinging the same to raised and lowered positions by longitudinal movement relative to the top-section, means carried by the top-section for locking the rod against longitudinal movement when the leg is lowered whereby to lock the leg in top-supporting position, said locking of the rod being 95 broken by bodily movement of the rod out of its locked position, means carried by the central support for moving the rod bodily 100 to break said lock when the top has been moved inwardly a predetermined distance, and means for preventing longitudinal 105 movement of the rod with respect to the central support whereby the leg will be 110 swung to raised position upon continued inward movement of the top-section.

11. In an extension table, the combination of a central support, an extension top-section, a supporting leg pivotally mounted on the top-section, a longitudinally movable rod arranged beneath the top-section to move in the direction of the sliding movement thereof, the rod being connected at its outer end with the leg for swinging the same to raised 115 and lowered positions by longitudinal movement relative to the top-section, means carried by the top-section for locking the rod 120

against longitudinal movement when the leg is lowered whereby to lock the leg in top-supporting position and to permit the top-section to be moved in and out with the leg

5 thus locked, means for releasing the rod from said locked position when the top-section has been moved inwardly a predetermined distance, and means for preventing inward movement of the rod with respect to 10 the central support after the release of the rod, for raising the leg by continued inward movement of the top-section.

12. In an extension table, the combination of a central support, an extension top-section, a supporting leg pivotally mounted on the top-section, a longitudinally movable rod arranged beneath the top-section to move in the direction of the sliding movement thereof, the rod being connected with the leg for 20 swinging the same to raised and lowered positions by movement longitudinally, means for so holding the leg locked in raised position that the top-section may be moved outwardly without lowering the leg, and a single means for moving the rod longitudinally to lower the leg when the table has been moved outwardly a predetermined distance and for determining the extent of the outward movement of the top-section.

30 13. In an extension table, the combination of a pedestal, a double-extension slide mounted thereon, a top-section fixedly connected to the most extendible section of said slide, a supporting leg pivotally mounted on the top-section, means carried by the top-section for swinging the leg to raised and lowered positions, means for locking the leg in raised position whereby the top-section may be moved inwardly and outwardly with 40 the leg locked up, and means fixed on the slide section upon which the first named slide section is mounted for actuating the first named means when the top-section has been moved outwardly a predetermined distance, whereby to release the leg from raised 45 position and cause the leg to be swung to a top-supporting position.

14. In an extension table, the combination of a central support, an extendible top-section mounted thereon, a supporting leg pivotally mounted on the top-section, a longitudinally movable rod carried by the top-section and connected at its outer end with the leg whereby upon longitudinal movement 55 of the rod with respect to the top section the leg will be swung to raised and lowered positions, the rod being provided intermediate its ends with a notch adapted to be engaged by an element fixed with respect to 60 the top-section when the leg is lowered to its supporting position, whereby to lock the leg in said position, abutment means carried by the central support in the path on the inner end of the rod, said inner end of the rod

being provided with means adapted to engage said abutment means when the top-section is moved toward the central support, the abutment means being shaped to actuate said rod and move the notch out of its said locking engagement and to operate the rod 70 to swing the leg to raised position.

15. In an extension table, the combination of a central support, an extendible top-section mounted thereon, a supporting leg pivotally mounted on the top-section, a longitudinally movable rod carried by the top-section and connected at its outer end with a leg whereby upon longitudinal movement of the rod with respect to the top-section the leg will be swung to raised and lowered positions, means for locking the rod against longitudinal movement when the leg is in lowered top-supporting position and whereby the top-section may be moved inwardly with the leg thus locked, means for releasing 80 said lock when the top-section has been moved inwardly a predetermined distance, and means for stopping longitudinal movement of the rod with respect to the central support after the said lock has been released, 90 whereby upon continued inward movement of the top-section the rod will effect swinging of the leg to raised position.

16. In an extension table, the combination of a central support, an extendible top-section slidably mounted thereon, a supporting leg pivotally mounted on the top-section, a longitudinally movable rod disposed beneath the top-section, the rod being provided at its outer end with a roller adapted 100 to roll upon a top-section element as the rod is moved longitudinally and to permit the inner end of the rod to swing vertically upon the roller as a fulcrum, the rod being connected with the leg for swinging the 105 same to raised and lowered positions by longitudinal movement of the rod, means for locking the rod from longitudinal movement to hold the leg in one of its operative positions, and means operable by sliding movement of the top-section for swinging the inner end of the rod on said fulcrum to release the rod from said locking position and permit the rod to be moved longitudinally to 110 operate the leg.

17. In an extension table, the combination of a central support, an extendible top-section slidably mounted thereon, a supporting leg pivotally mounted on the top-section, a longitudinally movable rod disposed 120 beneath the top-section, a pivotal link connection between the outer end of the rod and the leg so arranged that upon movement of the top-section to its most inward position the leg will be swung to raised position and the link moved past a dead center position effecting locking of the leg in said raised 125 position, means for stopping movement of

the rod longitudinally with respect to the central support when the top-section is moved outwardly a predetermined distance whereby upon continued outward movement thereof the rod will release the said link from its locking position and swing the leg to lowered position, the central support being provided with an abutment, the inner end of the rod being provided with means for engaging said abutment when the top-section is moved inwardly, whereby to stop

longitudinal movement of the rod with respect to the central support and swing, by continued inward movement of the top-section, the leg to raised position and effect 15 through said link connection locking of the leg in said raised position.
